UNITED STATES PATENT OFFICE

BRUCE L. FORBES, OF NEW MARTINSVILLE, WEST VIRGINIA

STRAW HOLDER AND DISPENSER

Application filed June 17, 1930. Serial No. 461,674.

My invention relates to a new and useful straw holder and dispenser and more particularly to a straw holder and dispenser wherein means is provided for preventing the straws contained in said holder and dispenser from being accidentally dislodged therefrom due to careless manipulation.

My invention still further relates to a straw holder and dispenser wherein the means for guarding against the spilling or dislodging of the straws consists of and is carried entirely by strong metallic parts, thereby preventing the breakage of the body of the holder proper which is usually made of glass or other decorative and fragile substance.

It has been the practice heretofore to provide a stop carried by and protruding inwardly through the wall of the holder, said stop or lug being adapted to limit the upward movement of the straw tray in the bottom of said holder when said tray is being raised to afford access to said straws. The repeated, more or less forceful impact of the metallic tray carrying the straws against the metallic stop embedded in the glass wall of the container resulted in fatiguing and ultimately breaking said wall.

Other devices heretofore known and used for limiting the upward movement of the tray containing the straws have generally consisted of more or less complicated structures which directly or indirectly were carried by or supported on the glass wall of the straw holder, thus exposing said wall to fatigue and breakage due to rough or careless manipulation to which straw holders and dispensers are necessarily subjected at the hands of the hurrying public.

It is therefore the object of my invention to provide a straw holder and dispenser wherein the glass wall is not subjected to any strain and wherein the means for limiting the upward movement of the straw tray is carried by said tray in connection with a central rod or stem along which said tray is adapted to slide.

To the above ends, my invention consists of a jar or holder, a central rod, carried by and projecting upwardly from the bottom of said holder, a stop carried by the top of said rod,

a straw tray movable within said holder upon said central rod, a connecting sleeve slidable over said central rod and having its lower end secured to said straw tray, and a closure for said holder carried by the top of said sleeve. 55

My invention further consists of various other novel features of construction and advantage, all as hereinafter described and finally claimed.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described. 60 65 70

In the accompanying drawings:

Fig. 1 represents a side elevation of a straw holder and dispenser embodying my invention; 75

Fig. 2 represents a vertical sectional view on line 2—2 of Fig. 1;

Fig. 3 represents a transverse sectional view on line 3—3 of Fig. 1;

Fig. 4 is a fragmentary vertical sectional view showing details of the construction. 80

Referring to the drawings, in which similar numerals of reference indicate corresponding parts, 1 designates a straw holder and dispenser comprising a jar or other receptacle 2, which is usually made of glass or any other substance and which may be of any desired shape or contour. 3 designates a guide rod which is preferably secured to the bottom 3a of the holder by means of the nuts 4 and flexible gaskets or washers 5. On the rod 3 is adapted to slide vertically the tray 6 which is adapted to fit within the holder 2 and which carries the straws 7 of the type usually employed for sipping beverages in 85 the well known manner. The tray 6 is secured to the lower end of the sleeve 8 which carries at its upper end the closure 9 for the top of the container, and which is adapted to slide over the rod 3. When the tray 6 is 90 95 100

resting at the bottom 3a of the holder 2, the closure 9 fits over the open upper end of said holder and the straws 7 are completely enclosed within the jar or holder 2.

5 When it is desired to use a straw, upward pull is exerted on the knob 10 of the lid or closure 9, thereby raising the tray 6 and straws 7 until said straws project above the top edge of the holder 2. In order to guard 10 against excessive raising of the tray 6 and the consequent spilling or dislodging of the straws 7 out of the holder 2, I provide the rod 3 with the enlarged head or stop 11 which engages the flange 12 in the bottom of the 15 sleeve 8, as will be understood from Figs. 2 and 4.

It will thus be seen that I have devised a 20 novel straw holder and dispenser of an extremely simple and durable construction 20 which prevents the accidental spilling or dislodging of the straws, and wherein the fragile glass wall of said holder is kept free from strain or impact and thus protected against breakage and fatigue.

23 While I have shown a stop 11 carried at the top of the central rod 3 and adapted to engage the inwardly deflected flange 12, at the lower end of the sleeve 8, it is within the 25 scope of my invention to vary these details 30 or provide other novel means for limiting the movement of the tray 6 in such a manner as to relieve glass wall 2 of the straw container 1, from fatigue due to constant, repeated strain which results from impact of 35 the tray 6 against a stop carried by the wall of said container or holder.

I am aware that the invention may be embodied in other specific forms without departing from the spirit or essential attributes thereof, and I therefore desire the present embodiment to be considered in all respects as illustrative and not restrictive, reference being had to the appended claim rather than to the foregoing description to 45 indicate the scope of the invention.

Having thus described my invention, what I claim as new and desire to secure by Letters Patent, is:

50 In a device of the character stated, a receptacle having an open top and a closed bottom, a guide rod extending upwardly from and detachably engaging said bottom, a tray slideable on said rod, a stop at the top of said rod for limiting the vertical movement of said 55 tray, a closure for the open top of said receptacle, and a sleeve connecting said closure and said tray and slideable over said rod, the latter extending substantially to the midheight of said receptacle, and said sleeve being substantially the same length as said receptacle, and having an inwardly deflected portion engaging said stop when elevated.

BRUCE L. FORBES.
